LIGHTNING-ARRESTER BLOCK

Frederick B. Johnson, Murrysville, Pa., assignor to Westinghouse Electric & Manufacturing Company, East Pittsburgh, Pa., a corporation of Pennsylvania

Application June 23, 1939, Serial No. 280,677

7 Claims. (Cl. 201—76/03)

My invention relates to high-resistance molded blocks of composition-material, such as are utilized as excess-voltage protective devices, because of their valve-type characteristic which enables them to readily discharge high currents at excessive voltages and to greatly increase their resistance to a discharge at normal voltages. Such blocks have terminal-ends which are commonly provided with a sprayed-copper coating in order to effect a reasonably good electrical connection, and in general, this sprayed-metal coating cannot be permitted to reach quite to the extreme edges or periphery of the end-surface, because of the necessity for keeping the sprayed copper off of the side walls of the block.

Such blocks display a very marked tendency to fall along their sides, and various remedies have been proposed therefor. In accordance with my present theories, I attribute such failures to the concentration of current at the edges of the sprayed-copper facings, and I explain the failures on the basis of the tendency of such high-resistance composition-materials to "hog" the current, that is, to reduce their resistivity when overheated by high current-flow, so that the spot which begins to become overheated by excessive current concentration gets worse and worse, by cumulative action, until a failure is produced.

It is an object of my invention to provide an improved block in which means are provided for preventing excessive current-concentrations around the sides.

More specifically, it is an object of my invention to provide a block which is molded with a peripheral layer of insulating composition material, or of material which is at least of a higher order of resistivity than the average resistivity of the main body-portion of the block. This material merges somewhat with the main body-portion of the block, at the junction point, creating a region of tapered resistivity, and it also provides an insulating, or extremely high-resistance, marginal space, at the ends, in which the sprayed-copper coating may terminate without creating a region of high current-density at the edge of the sprayed-copper coating.

With the foregoing and other objects in view, my invention consists in the structures, compositions and methods hereinafter described and claimed, and illustrated in connection with the accompanying drawing, wherein:

Figure 1 is a plan view of a block made in accordance with my present invention;

Fig. 2 is a cross-sectional view thereof, on a 55

sectional plane indicated by the line II—II in Fig. 1; and

Fig. 3 is a cross-sectional view illustrating a modification.

In the form of my invention shown in Figs. 1 and 2, I utilize a molded high-resistance block having a main body-portion 1, which is composed of silicon-carbide granules or crystals and a binder. I may utilize, for the binder, any one of various ceramic or clay binders, or other materials including various silicates, but at present I prefer to utilize a binder of water glass, which is a commercial, water-soluble sodium silicate, which may be defined as any one or more of a number of chemical compounds consisting of various proportions of silica, soda, and water.

By the term block I means to refer to any suitably shaped mass of material, the illustrated block being in the form of a short length of a cylindrical body of material having flat ends, although I wish it to be understood that I am not limited to any particular length or shape.

In accordance with my present invention, the block is formed, preferably in the original molding process, with a small annular edge-portion 2 consisting of a molded composition-material also utilizing a water glass binder, but with a granular filler-material which is substantially an insulator, or which at least results in a product having a higher order of resistivity than the main body-portion 1. The filler-material which is utilized in the peripheral portion 2 may be finely subdivided feldspar, sand, any one of various metallic oxides, or almost any other finely divided non-binding material, insulating or non-insulating, even including silicon-carbide crystals of a different size or quantity than the crystals which are utilized in the main body-portion 1.

In the process of manufacture, various methods are available for so molding the block that it has the main body-portion 1 and the marginal portion 2 as described, after which the whole body, consisting of the portions 1 and 2, is dried out, by baking, to produce a unitary, cohering mass. In a preferred process, the marginal portion 2 is first packed into the mold, after which the main body-portion 1 is introduced, the whole being suitably pressed and baked.

Because of the similarity of the binders, the portions 1 and 2 readily merge together, providing an intermediate-region 3 in which the high-resistance property of the main central block 1 tapers off toward the insulating, or at any rate still higher-resistance, properties of the marginal rim 2. In this manner, I avoid sharp concentra-

tions of current along or near the edges of the main body-portion 1.

After the molding and baking operations, the block is provided with terminal conductive coatings 4 and 5 of sprayed copper or other good conducting material, preferably metallic, and this sprayed-copper coating preferably terminates, at its peripheral edge, in the flat end-portions of the marginal rim-portions 2 of the molded block, so as to avoid the peripheral current-concentrations which are obtained when the marginal edge of the copper-spray terminates on the flat end-surface of the main body-portion 1.

In Fig. 3, I show a modified form of embodiment of my invention, in which the marginal cylindrical-shaped annular molded portion 2 is replaced by two conical portions 6 and 7 which encircle the main body-portion 1 only at the flat ends which are coated with the sprayed-copper coatings 4 and 5, so that the main body-portion 1 has a greater diameter at its central portion than at its ends. This necessarily results in some concentration of current around the edges of the main body-portion 1, at the reduced-area ends, where the diameter of the main body-portion 1 is reduced by reason of the presence of the conical peripheral portions 6 and 7, but the blended junction-portions 8, where the material 6 and 7 joins with the main body-portion 1, serves somewhat in the capacity of providing a peripheral region 9 of gradually increasing resistivity, in the ends of the block, so as to spread out the current-concentration over a wider area, thus reducing its intensity.

My invention, particularly in the preferred form shown in Figs. 1 and 2, has resulted in blocks of improved performance, and by making the cylindrical marginal portion 2 with a filler material which is less abrasive than the silicon carbide of the main body-portion 1, I secure a saving in the wear and tear on the molds which are needed in the manufacture of the block.

I claim as my invention:

1. An excess-voltage protective device comprising a flat-ended high-resistance block comprising a main portion of high-resistance molded composition-material terminating in said flat ends and having a valve-type characteristic which enables it to readily discharge high currents at excessive voltages and to greatly increase its resistance to a discharge at normal voltages, a closely adhering edge-portion extending around at least each end of said main portion and also terminating in said flat ends, said edge-portion being of a higher order of resistivity than the average resistivity of said main portion, and a coating of a good conducting material covering each of the flat ends, each good-conducting coating covering all of said main portion and at least some of the surrounding edge-portion at its end of the block.

2. An excess-voltage protective device comprising a flat-ended high-resistance block comprising a main portion of high-resistance molded composition-material terminating in said flat ends and having a valve-type characteristic which enables it to readily discharge high currents at excessive voltages and to greatly increase its resistance to a discharge at normal voltages, a

closely adhering edge-portion extending around, and entirely covering, the sides of said main portion, said edge-portion also terminating in said flat ends, said edge-portion being of a higher order of resistivity than the average resistivity of said main portion, and a coating of a good conducting material covering each of the flat ends, each good-conducting coating covering all of said main portion and at least some of the surrounding edge-portion at its end of the block.

3. An excess-voltage protective device comprising a flat-ended molded high-resistance block adapted to carry current from end to end thereof and comprising two different mixtures, each composed of finely subdivided material and a binder, the main portion of the block being of a mixture resulting in a high-resistance body-portion terminating in said ends and having a valve-type characteristic which enables it to readily discharge high currents at excessive voltages and to greatly increase its resistance to a discharge at normal voltages, the sides of said main portion being surrounded, and entirely covered, by material of a different mixture resulting in a surrounding-portion of a higher order of resistivity than the average resistivity of said main portion, a common binder being utilized for both mixtures, and the whole being molded together in an adhering integral mass, and a coating of a good conducting material covering each of the flat ends, each good-conducting coating covering all of said main portion and at least some of the surrounding-portion at its end of the block.

4. An excess-voltage protective device comprising a flat-ended molded high-resistance block adapted to carry current from end to end thereof and comprising two different mixtures, each composed of finely subdivided material and a binder, the main portion of the block being of a mixture resulting in a high-resistance body-portion terminating in said ends and having a valve-type characteristic which enables it to readily discharge high currents at excessive voltages and to greatly increase its resistance to a discharge at normal voltages, the sides of said main portion being surrounded, and entirely covered, by material of a different mixture resulting in a surrounding-portion of a higher order of resistivity than the average resistivity of said main portion, a common binder being utilized for both mixtures, and the whole being molded together in an adhering integral mass, and a coating of a good conducting material covering each of the flat ends, each good-conducting coating covering all of said main portion and at least some of the surrounding-portion at its end of the block.

5. The invention as defined in claim 2, characterized by said edge-portion comprising a molded mixture including a finely subdivided filler and a binder comprising a water-soluble silicate.

6. The invention as defined in claim 3, characterized by the common binder being an aqueous mixture including water-soluble silicate.

7. The invention as defined in claim 4, characterized by the common binder being an aqueous mixture including water-soluble silicate.

FREDERICK B. JOHNSON.
